PORTABLE AM RADIO

John T. Houlihan, Manlius, N.Y., assignor to
General Electric Company

Filed May 1, 1972, Ser. No. 249,480

Term of patent 14 years

Int. Cl. D14—03

U.S. Cl. D56—4 B

FIG. 1 is a front elevational view of a portable AM radio in accordance with my design;

FIG. 2 is a rear elevational view;

FIG. 3 is a left side elevational view;

FIG. 4 is a right side elevational view;

FIG. 5 is a top plan view; and

FIG. 6 is a bottom plan view.

I claim:

The ornamental design for a portable AM radio, as shown.
